UNITED STATES PATENT OFFICE.

JOHN KNIERIEM, OF GLENDALE, NEW YORK, ASSIGNOR TO METROPOLITAN-COLUMBIA MFG. CO. INC., A CORPORATION OF NEW YORK.

DESIGN FOR A BODY FOR LIGHTING FIXTURES OR ARTICLES OF ANALOGOUS NATURE.

Application filed February 25, 1928. Serial No. 25,591. Term of patent 3½ years.

To all whom it may concern:

Be it known that I, JOHN KNIERIEM, a citizen of the United States, and a resident of Glendale, county of Queens, and State of New York, have invented a new, original, and ornamental Design for a Body for Lighting Fixtures or Articles of Analogous Nature, of which the following is a specification, reference being had to the accompanying drawing, forming a part hereof.

The single figure of the drawing shows a perspective view of the body for lighting fixtures or articles of analogous nature which has arms for the support of candles or drop lights.

I claim:

The ornamental design for a body for lighting fixtures or articles of analogous nature substantially as shown and described.

JOHN KNIERIEM.
